UNITED STATES PATENT OFFICE.

DUDLEY W. IMUS, OF LOS ANGELES, CALIFORNIA.

SHOW-CASE FOR DISPLAYING PICKLES AND THE LIKE.

No. 899,052.

Specification of Letters Patent.

Patented Sept. 22, 1908.

Application filed May 5, 1908. Serial No. 431,052.

To all whom it may concern:

Be it known that I, DUDLEY W. IMUS, a citizen of the United States, residing at Los Angeles, California, have invented a new and 5 useful Show-Case for Displaying Pickles and the Like, of which the following is a specification.

This invention relates to means for displaying goods contained in jars or other receptacles, in a manner suitable for use in a 10 grocery store to attract customers.

The invention is designed largely to display pickles and like goods in an attractive manner in the ordinary opaque earthen jars 15 so that it will be unnecessary for merchants to purchase more expensive glass jars in order to display the pickles so they may be clearly seen by prospective customers.

Experience has shown that when pickled 20 goods are kept submerged in brine or vinegar the air must have free access to the pickling or preserving fluid or the proper preservation of the goods will be interfered with, and also the attractive appearance of the goods destroyed by reason of scum rising to the 25 surface of the preserving liquid.

An object of this invention is so to display such goods that there will be nothing to hinder them from being clearly seen, but at the 30 same time, insects will be kept out and free access of air permitted.

Other objects are to provide for compact and convenient arrangement of the containing vessels; for ready access thereto; and 35 for convenient storage of ladles and the like used in removing the contents of said receptacles.

Other objects and advantages may herein-after appear.

40 Referring to the accompanying drawings which illustrate the invention Figure 1 is an isometric perspective showing a set of jars mounted in a show case embodying the invention. Fig. 2 is a rear view of the case. 45 Fig. 3 is a vertical section on line X³ of Figs. 1 and 2. Fig. 4 is an enlarged sectional detail showing more clearly the manner of covering the jars.

The supporting means of the show case includes a frame having side-pieces 1 and 2, between which are mounted a plurality of shelves 3, 4 and 5 arranged in a stepped series and supported in any suitable manner as by boards 6 nailed to said side pieces, to per-

form the function of cleats. Upon each of 55 the shelves is mounted a row of open-topped receptacles desirably jars 7 of uniform height. Each row of jars is provided with a lid hinged at 8 to cover the same, said lid consisting of a sash 9 having an under section of 60 wire screen 10 provided with a cut-away portion 11 over the top of each jar to form a sight-opening for the clear observation of the contents of the jars.

12 designates a metal selvage extending 65 around the edge of each opening 11 in the screen, and 12' a selvage extending around the outer edges of the screen.

The sashes are each provided with an upper transparent section 13 preferably of 70 glass. As best shown in Figs. 3 and 4, there is a clearance between screen 10 and glass 13 so that air may readily ascend around the jars and pass downwardly thereto between the screen and glass. When pickled goods 75 are placed in the jars, this construction tends to preserve them, it being impossible to keep such goods fresh when the container is occasionally opened but kept air-tight during the intervals.

80 The lid for the lower row of jars is, in the embodiment of the invention illustrated in the drawings, supported wholly by the jars when in the closed position. All the lids should rest principally on the tops of the jars 85 to insure a close fit so that insects cannot enter between the screen and the tops of the jars, but the two upper lids are shown touching lightly at each end upon the tops of casings or hollow posts 14. Said posts 14 may 90 contain counterbalancing weights 15 fastened to cords 16 led over pulleys 17 to the sash. Said counterbalancing weights tend to prevent the lids closing with a jar 95 that might break the glass. In order to further deaden the jar upon the glass, the sashes are provided with a layer 18 of felt or like material above and below the edges of the glass.

100 It is important that the screens be provided with the openings 11 above the tops of the jars, because the contents of a jar cannot be clearly seen when covered by an unbroken screen, and a clear disclosure of the contents of the jars aids in awakening the interest of 105 customers and therefore in making sales of goods offered for sale in the show case.

The sashes are preferably countersunk on

their lower sides at 19 for the reception of the screen. Buttons 20 may be provided to detachably hold the screen in place, it being desirable to remove the screen occasionally to 5 clean the under side of the glass.

21 are knobs for lifting the sash.

The space at the rear of the case may be partitioned off by upright cross-wall 22 and division walls 23 to make suitable provision 10 for ladles 24 for dispensing the goods; said ladles being desirably kept in water in jars 25 and held in place by hooks 26. The compartments between jars 25 may be utilized to contain the packages in which the pickles 15 are sold.

The side walls 1 and 2 of the case may rise considerably above the lids to shield the glass in the sash at all times. A back-board 27 is provided at the rear of the case for a similar 20 purpose.

28 designates stops in the form of strips extending along the top of the shelves near their rear sides to prevent the jars from being pushed too far back to sit squarely under the openings 11 in the screens.

One important feature of the invention is that the case is so constructed that the air has access to the jars from all sides thereof. The entire case is raised somewhat from the 30 floor being desirably mounted on casters 29 which allow the air to pass under the case to the rear side of the front row of jars and also above the cross wall 22 and thence upwardly between the middle and rear row of 35 the jars. The appearance of the show case is made more attractive and the air allowed to circulate more freely thereunder by reason of the front shelf 3 and the rear platform 30 being raised above the floor a suitable 40 distance.

I claim:

1. In a device of the character described, a frame, a plurality of shelves arranged on said frame in a stepped series, open-topped 45 receptacles on said shelves, and hinged lids to cover said receptacles, said lids carrying a transparent covering for said receptacles and admitting air to the receptacles when closed.

2. In a device of the character described, 50 supporting means, a plurality of receptacles mounted thereon, and a lid to cover said receptacles said lid comprising a sash and a pane of glass therein, said lid resting on said receptacles when down, said sash being pro-

vided with padding adjacent said pane of 55 glass.

3. In a device of the character described, supporting means, a receptacle mounted thereon, a lid to cover said receptacle, said lid comprising a sash and a pane of glass 60 therein, hinges for said lid, a stop against which said lid abuts to limit the opening movement thereof, a flexible connection fastened to said lid, a weight fastened to said connection tending to open said lid, and 65 padding at the edges of said glass to prevent the jarring against the glass when said lid strikes said stop.

4. In a device of the character described, a frame, a plurality of supports on said frame, 70 open-topped receptacles mounted in a stepped series on said supports, and lids for said receptacles, said lids carrying a lower section of screen cut away to permit a clear view of the interior of said receptacles, and an upper 75 section of transparent material.

5. In a device of the character described, a receptacle, a transparent cover therefor, 80 said cover being spaced above said receptacle to allow entrance of air into said receptacle, and means to prevent entrance of insects through the space between said cover and receptacle.

6. In a device of the character described, a receptacle, a transparent cover therefor, 85 said cover being spaced above said receptacle to allow entrance of air into said receptacle, and a screen to prevent entrance of insects through the space between said cover and receptacle.

7. In a device of the character described, supporting means; a row of receptacles thereon; and a common lid for said row of receptacles, said lid comprising a sash, a lower section of wire screen adapted to close 95 down upon said receptacles and cut away inside the tops thereof, and a section of transparent material spaced above said section of screen.

In testimony whereof I have hereunto 100 signed my name in the presence of two subscribing witnesses at Los Angeles, in the county of Los Angeles and State of California, this 29th day of April, 1908.

DUDLEY W. IMUS.
